CLINTON W. RUSSELL, OF DETROIT, MICHIGAN.

BUNK FOR LOGGING-CARS.

1,124,530.

Specification of Letters Patent.

Patented Jan. 12, 1915.

Application filed February 2, 1914. Serial No. 816,025.

To all whom it may concern:

Be it known that I, CLINTON W. RUSSELL, a citizen of the United States of America, residing at Detroit, in the county of Wayne 5 and State of Michigan, have invented certain new and useful Improvements in Bunks for Logging-Cars, of which the following is a specification, reference being had therein to the accompanying drawings.

10 The invention relates to bunks for logging cars, and has more particular reference to the construction of a collapsible end stake and mechanism for supporting the same.

15 In the drawings: Figure 1 is a perspective view of the bunk; Fig. 2 is a longitudinal section through one end of the bunk showing the stake in its locked position; Fig. 3 is a similar view showing the collapsed position of the stake; Fig. 4 is a cross section; and 20 Fig. 5 is a sectional plan view of the latch mechanism.

25 In the hauling of large and heavy timber, the logs are supported upon bunks on independent trucks, and are held from rolling off these bunks by chocks or end stakes. To permit of loading and unloading, at least one of the chocks or end stakes must be removed or depressed, while in normal position these parts are subjected to very heavy 30 stresses. Furthermore, when the chock or stake is to be released it is frequently under load and the releasing mechanism must therefore be operable under such load.

35 My improved construction is designed to obtain a bunk having an end stake which may be readily released even where under the load of the log, and further, one in which the stake is effectively braced in its normal position so as to be able to withstand any 40 load to which it may be subjected.

45 A is a bunk of any suitable construction, but is shown formed of a modified I-beam, having a head portion B of spear-shaped cross section. The ends C are bifurcated to receive the stake D, which is preferably constructed as follows: E are oppositely-projecting lugs or trunnions at the base of the stake D, which engage segmental, grooved bearings F in the furcations of the end portion C. G is a chain passing through an eye H in the upper end of the stake and extending downward in inclined direction to the opposite sides of the portion C, being secured at its ends by passing through an 50 apertured lug I and having link-engaging locking members J adjacent thereto. The

trunnions E are movable in the segmental grooves F to adjust the stake from a collapsed or depressed position, where its outer end is below the plane of the bunk, as shown in Fig. 3, to an upright position, as shown in Fig. 2. In the latter position the stake is normally held by a dog K pivoted between the furcations of the portion C and having a hook K' which engages a lip or laterally-extending lock L on the inner side of the stake. The dog K has an inwardly and downwardly extending arm K² which is adapted for engagement with a second dog or locking lever M, also between the furcations of the bunk. This lever M is pivoted upon a pin N, while the dog K is pivoted upon a pin O, both extending laterally through the bunk.

With the construction as thus far described, when the dog K has its hook K' in engagement with the lip or lock L and its arm K² in engagement with the lever M, the stake D will be supported in its normal upright position, as shown in Fig. 2. In this position the chain G which connects with the upper end of the stake will be placed under tension whenever any lateral pressure of the log is exerted against the stake, and the only stress transmitted directly from the stake to the bunk is the downward thrust which is resisted by the hook K' engaging the lip L. When, however, this hook is withdrawn the stake is free to drop, the trunnions E passing around the segmental slots and the chains swinging into the position shown in Fig. 3. To disengage the hook K' from the lip L the lever M must be withdrawn from the arm K² to permit the latter to swing around the pivot O. The engagement between the arm K² and the lever M, as shown in Fig. 2, is such that there is no tendency to unlock, due to the stress exerted through the dog K, but to hold this lever from accidental disengagement as well as to provide a means for releasing it when desired an actuating connection is provided. This preferably consists of a rod P which extends longitudinally of the bunk, being slidably supported in bearings formed in transverse webs Q of the bunk and provided at one end with a laterally offset portion P' which passes through a slot R in the end of the transverse web Q'. S and S' are handles secured to the rod P for rocking and moving the same longitudinally, and T is a keeper member pivoted

to the web of the bunk beam, which may be engaged with the handle S to prevent the accidental rocking of the same. The arrangement is such that when the handles S and S' are in inclined position, as shown in Fig. 1, the rod P may be slid longitudinally, and as the inner end of this rod has a hook P² engaging the end of the lever M, the latter will be rocked so as to disengage the arm K² of the dog K. On the other hand, when the handle S is rocked into vertical position, the laterally offset portion P' of the rod P will engage with the web Q' so as to lock it from longitudinal movement.

In operation, whenever the rod P is manipulated to disengage the lever M and release the dog K, the stake D will drop by gravity and assume the position shown in Fig. 3. In this position the dog may be freely rolled on or off from the end of the bunk without interference from the stake. When the dog is loaded, by merely lifting the end of the stake D it may be raised to the position shown in Fig. 2, and in so doing a portion of the stake bearing against a lug K³ on the dog K will rock the latter into a position where the arm K² is engageable with the notch M' in the lever M. The operator then adjusts the rod P through the handle S', which is sufficiently near in location to the stake D to be operable when the latter is raised, and thus the lever M is forced into engagement with the arm K² and is locked by the offset portion P' of the rod P engaging the web Q'. The latch T is then dropped over the handle S which will preclude any possibility of the shaking loose of the locking mechanism.

When the lock is to be released, the operator, standing at the opposite end of the bunk, can disengage the latch T, rock the handle S and longitudinally adjust the rod P, and thereby disengage the lever M from the dog K. The multiplication of the lever is so great that this movement may be accomplished with ease, even where the stake and chains G are under heavy stress due to the load of the dog.

What I claim as my invention is,—

1. The combination with a bunk, of an end stake therefor having its lower end provided with a segmental sliding engagement with said bunk, an inclined link connecting the upper end of said stake with the bunk, and a removable support for the lower end of said stake when in its upright position.

2. The combination with a bunk, of an end stake, an inclined link connecting the upper end of said stake with said bunk, means for slidably engaging the lower end of said stake with a segmental portion of said bunk, permitting of the adjustment of the same and the inclined link connected thereto to a position below the top of the

bunk, and a removable support for said stake in its raised position.

3. The combination with a bunk, of an end stake therefor, an inclined link connecting the upper end of said stake with said bunk, means for permanently slidably engaging the lower end of said stake with said bunk to permit of the adjustment of the same and the inclined link into a position below the upper edge of the bunk, a dog for supporting the lower end of said stake when in its upright position, and means for releasing said dog operable from the opposite end of the bunk.

4. The combination with a bunk having a bifurcated end, of an end stake having its lower end provided with a segmental sliding engagement with the bifurcation of the bunk, an inclined link or brace connecting the upper end of said stake with said bunk, a locking dog for supporting the lower end of said stake when in upright position, and means operable from the opposite end of the bunk for releasing said locking dog.

5. The combination with a bunk having a bifurcated end with segmental grooved bearings formed in the opposite furcations thereof, of a stake having trunnions at its lower end engaging said segmental, grooved bearings, an inclined brace connection between the upper end of said stake and said bunk, a dog between the furcations of said bunk forming a support for said stake in its upright position, a locking lever for said dog, and a rod extending longitudinally of said bunk for actuating said locking lever to release said dog and disengage the same from said stake.

6. The combination with a bunk having a bifurcated end, of a stake having its lower end slidably engaging the furcations of said bunk in the different positions of said stake, a chain connected with the upper end of said stake and extending in an inclined direction to said bunk and secured thereto, a dog between the furcations of said bunk for supporting the lower end of said stake in its upright position, and means extending longitudinally of said bunk for locking and for releasing said dog.

7. The combination with a bunk having a bifurcated end with segmental grooves in the inner faces of the furcations thereof, of a stake having trunnions at its lower end slidably engaging said segmental groove, a chain connecting the upper end of said stake and inclining downward and inward on opposite sides thereof, anchoring connections for the lower ends of said chain upon said bunk, a rockable dog between the furcations of said bunk having a hooked engagement with a supporting bearing at the lower end of said stake, an arm projecting from said dog, a lever for engaging said arm to hold the same from rocking move- 13

ment, and a rod for actuating said lever extending longitudinally of said bunk.

8. The combination with a bunk having a bifurcated end and segmental, grooved bearings in the inner faces of the furcations thereof, of a stake provided with trunnions at its lower end for engaging said segmental, grooved bearings, a chain connected with the upper end 10 of said stake, extending downward therefrom in an inclined direction and having an anchoring connection with said bunk, a rockable dog between the furcations of said bunk having a hooked supporting engagement 15 with the lower end of said stake, an arm extending inward and downward from said dog, a lever notched for engagement with said arm, a rod longitudinally, adjustably secured to said bunk and connected to 20 said lever, and means for locking said rod from longitudinal movement.

9. The combination with a bunk, of an end stake having a collapsible engagement therewith, a dog for supporting said stake 25 in its normal upright position, a locking lever for said dog, and a rod extending longitudinally of said bunk connected with said

lever and having an offset portion engageable with the coöperating bearing on said bunk by a rocking movement to lock said 30 rod from longitudinal movement.

10. The combination with a bunk, of an end stake therefor, a chain connected with the upper end of said stake and extending in an inclined direction to said bunk, an 35 apertured lug on said bunk for engaging said chain, a link-engaging locking member adjacent to said lug, and a removable support for the lower end of the stake.

11. The combination with a bunk, of an 40 end stake therefor, an inclined link connection between the upper end of said stake and said bunk, a removable support for the lower end of said stake when in its upright position, and means permitting said lower 45 end to move inwardly of the bunk when released from said support.

In testimony whereof I affix my signature in presence of two witnesses.

CLINTON W. RUSSELL.
